CLAIM

The ornamental design for a tread band for pneumatic tire, as shown and described.

DESCRIPTION

FIG. 1 is a perspective view of the right-hand side of a tread band for pneumatic tires showing our new design;

FIG. 2 is a right side elevational view thereof;

FIG. 3 is a front elevational view thereof, it being understood that the tire tread pattern repeats circumferentially throughout the outer circumference; and,

FIG. 4 is a left side elevational view thereof.

In the drawings, the broken lines defining the sidewall, inner bead and the peripheral boundary between the claimed tire tread and the unclaimed sidewall depict environmental subject matter that forms no part of the claimed design.
